Primary Examiner — John Windmuller*Assistant Examiner* — Steven Czyz(74) *Attorney, Agent, or Firm* — Millen, White, Zelano & Branigan, P.C.(57) **CLAIM**

The ornamental design for a sink saver, as shown and described.

DESCRIPTION

FIG. 1 is a top and front perspective view of the sink saver showing my new design.

FIG. 2 is a top view thereof.

FIG. 3 is a side view thereof.

FIG. 4 is another side view thereof.

FIG. 5 is a bottom view thereof.

FIG. 6 is another side view thereof; and,

FIG. 7 is another side view thereof.

The broken lines in the figures represent portions of the sink saver that form no part of the claimed design.
